UNITED STATES PATENT OFFICE.

COBURN F. VALLEY, OF CUYAHOGA FALLS, OHIO, ASSIGNOR TO LLOYD E. ELLSWORTH,
OF CUYAHOGA FALLS, OHIO.

CARRIER FOR BRAIDING MACHINES.

Application filed May 18, 1925. Serial No. 30,934.

To all whom it may concern:

Be it known that I, COBURN F. VALLEY, a citizen of the United States, residing at Cuyahoga Falls, in the county of Summit and State of Ohio, have invented certain new and useful Improvements in Carriers for Braiding Machines, of which the following is a specification.

My invention is an improvement in carriers for braiding machines.

In the type of carrier now commonly used, the spool or bobbin is mounted on an axis carried near the top of the carrier frame. This structure results in a top-heavy or unstable carrier since its center of gravity is too high above the carrier base. When pulling forces are applied to the top of the carrier they will be assisted by the unstable condition of the carrier, in breaking it off its base. It is, therefore, necessary to continually stop the braider to replace broken carriers and other parts, which results in lower production and higher cost of operation.

An important object of my invention is the provision of a carrier of the above named character in which the bobbin is supported at a point near the base of the carrier so that the center of gravity of the carrier will be maintained at a low point at all times, thus reducing the tendency of the carrier body to break off at or near its base.

Another object of my invention is to provide a device of the above named character, having an automatic braking device for the spool or bobbin, so as to maintain the thread or wire taut under all conditions during the braiding operation.

Another object of my invention is to provide a device of the above named character which will be more compact than the devices heretofore used and which will be more durable and less expensive to manufacture.

Other objects and advantages of my invention will become more apparent as the description of an embodiment thereof progresses, reference being made to the accompanying drawings forming a part of this specification and in which like numerals are employed to designate like parts throughout the same.

In the drawings—

Fig. 1 is a front elevation of the carrier showing the tension regulator in normal operative position; 55

Fig. 2 is a side longitudinal section of the same, and

Fig. 3 is a top plan view of the carrier.

In the drawings, 5 represents a table of the usual type used in braiding machines. The table is provided with the usual horning gears for propelling the various carriers over the table top 7. The course of the carriers is determined by track slots in the table top through which the base of each carrier passes. The slotted tables referred to are to be found in the usual type of braiding machines and are not claimed as a separate part of this invention. 60 65

An embodiment of my invention comprising a carrier is illustrated in the drawings and includes a base composed of plates 9 and 10 spaced by a guide device 11. It will be noted that the lower plate 10 is of smaller dimensions than the upper plate 9 and is provided with a depending stud 12 slightly eccentrically located on the under side of plate 10. It is desired to have the stud formed in the lower plate at a point centrally of the width but slightly towards the left as shown in Fig. 2. This arrangement provides for a more perfect balance of the carrier and permits it to be operated at a greater speed than those in use today. The stud engages sockets formed in the driving gears 80 85 on the table and passes the carrier along in its travel around the table. 70 75

The guide device 11 rides within the track slots in the table top and is pointed on each end as shown at 13 so that it will more readily take the desired path when crossing slots in the table top. 90

The upper surface of the lower plate 10 slides over the under surface of the table top, while the under surface of the top plate 9 slides over the upper surface of the table top. The engaging surfaces of the plates provide considerable bearing surface for the carrier and form a very rigid construction especially when a pull is exerted on the top 100 of the carrier at an angle to the vertical, as by extreme tension on the wire 23.

A spool supporting frame 14 is formed on the upper plate and is preferably reinforced where it joins the base. The frame extends upwardly as shown and terminates in a 5 transverse bearing supporting member 15.

A sleeve 16, preferably of glass, is removably carried within the member and is provided with an annular top flange 17 rounded on its inner and top edges. I have specified the use of a glass sleeve since it is as 10 efficient as a metal or other sleeve and is less expensive to manufacture, although it is to be understood that I may use a sleeve made of any desired material.

15 The sleeve extends through the supporting member and is grooved near its base at 18, to receive a locking ring or twisted wire 19. Substantially midway of the frame 14 I have provided aligned bearing openings 20 to receive a shaft 21. The shaft is in the form of a pin having a head 20 and having a pin P for engaging the frame to lock the shaft against rotation. The other end of the shaft is grooved at G to receive a 25 resilient locking pin P'. A spool or bobbin 22 having a winding of thread or wire 23 or the like, is rotatably and removably mounted on the shaft 21 and when in operative position is positioned between the frame side 30 members 14 approximately midway of their respective ends to rotate therebetween.

An automatic brake device is mounted on one of the members 14 as shown more clearly in Fig. 2. This brake device consists of an 35 operating lever 24 pivoted at 25 and having oppositely disposed arms 26 and 27. A brake band 28 which preferably consists of a length of wire, is secured at each of its ends to one of the arms 26 and 27, respectively. I do not wish to be limited to the use of a wire brake band as it is obvious that a band of any other material such as rawhide or fibrous material would accomplish the same results. The brake band is 40 seated within an annular groove 29 on the spool periphery, as shown, and when the lever 24 is rocked upwardly, the brake band will be loosened and the spool will be free to turn on its axis, but when the lever is 45 rocked downwardly, the band will be tightened from both ends and the spool will be securely held against rotation. I provide a means for normally forcing the lever 24 downwardly which consists of a bracket B 50 mounted on the frame 14, through which is threaded a sleeve S. A guide rod is pivotally connected to the lever 24 and extends into the sleeve S. A coil spring S' is carried by the rod between the lever and the sleeve and normally is under compression. Greater compression may be supplied to the 55 spring by screwing the nut N and sleeve S downwardly.

Guides 30 and 31 are secured to the frame 60 members 14 and consist preferably of ar-

cuate-shaped members slotted at 32 and secured at their respective ends to the frame 14 as shown at 33, although it is to be understood that I may use guides of any desired shape or outline and further that I 70 do not wish to be limited to the use of guides which are slotted, since I may use grooved guides or guides which in any other way are adapted to the purpose for which my preferred form is used.

75 Referring to Fig. 2 of the drawings, it will be seen that the spool axis intersects about midway, imaginary straight lines drawn from one end of the guides to the other end of the respective guide.

80 A tension regulating device is provided to travel along the path of the slotted guide rails 30 and 31 and consists of a main body portion 34 having spaced spindle supporting arms 35 extending upwardly therefrom and provided with aligned openings for carrying a spindle 36. A grooved roller 37 rotates with the spindle and is mounted between the arms. Roller bearings 38 are provided on the ends of the spindle and are 85 adapted to engage and travel within the slots 32. A second spindle 39 is mounted transversely of the main body of the tension regulator and extends outwardly on both sides thereof. This spindle is provided with roller bearings 40 which engage and 90 travel within the slots 32 as shown. The extreme outer ends of the spindle 39 are each provided with cone-shaped tripping members 41 which are adapted to engage pins, or the like (not shown) for stopping the machine. These pins are carried on the table in the path of travel of the carrier and are tripped when the winding 23 breaks and allows the tension device to drop to the 95 lower part of the carrier. If, for any reason, the brake band about the spool 22 should become loosened or slip as when the tension adjustment on the brake lever 24 is too weak, and the winding accumulates 100 more slack than is necessary to hold the regulator to the desired lifted position, the regulator will travel down the guide rails toward the base thereof until the tripping members 41 engage tripping pins (not 105 shown) on the table and stop the machine as described above. In normal operation, the tension regulator is held considerably above the lower portion of the carrier. In order to vary the weight of the regulator, I 110 have provided removable weighting plates 42 which may be added thereto as desired.

115 The winding 23 passes from over the rear of the spool or bobbin and under the groove in the roller, thence upwardly over the roller 120 and is threaded through the sleeve 16. From the carrier the winding passes upwardly to the former bar (not shown).

125 In operation, as the carriers are started into motion on the table, a considerable ten-

sion is applied to the winding 23 which will lift the tension regulator in the guides to a point where its weight equalizes the pull on the winding 23, and allows the regulator to be maintained in suspended position. Under ordinary operating conditions, this pull will be sufficient only to lift and suspend the regulator at a point as shown approximately in Fig. 2.

10 As the carrier passes around the table it travels in a tortuous path and as it approaches and passes the outermost points with respect to the periphery of the table, the tension on the winding will be increased 15 to a point where the regulator will lift in the guides and engage the lever and release the brakeband so that the spool will feed more of the winding to the former bars. As more slack is given the winding, the carrier 20 approaches the innermost portion of the table and the regulator will drop out of contact with the spring pressed brake lever, thus resetting the brake and locking the spool against rotation. During the latter 25 part of the cycle of operations, the carrier has approached and passed the innermost points of travel with respect to the periphery of the table. The entire cycle of operations is repeated continuously many times 30 while the carrier is traveling around the table. As a result of the automatic tension controlled feeding means, I have provided a carrier which may be operated for a long period of time without necessity of repair. 35 By providing means for adjusting the brake tension and means for varying the weight of the carrier, I have increased the limits of tension under which the device may efficiently operate. In fact, the device will operate 40 over a wide range for braiding any materials which may more or less change the degree of tension under which the device will efficiently operate.

Then it will be seen that the tension on 45 the winding will be automatically regulated without the necessity of stopping the machine to make adjustments. This results in great time saving, faster operating speed and a lower manufacturing cost.

50 When it is desired to vary the degree of tension under which the regulator will operate to set and release the brake mechanism, it is only necessary to add or take away one or more of the weighting plates 42 or vary 55 the compression of spring S', or both.

Various changes in the construction and operation of my invention may be resorted to without departing from the spirit of my invention or the scope of the subjoined 60 claims.

What I claim is:

1. A spool carrier comprising a base, a frame, a spool carried by the frame, a brake for the spool, and an automatic tension regulating device movable in a curved path

about said spool and adapted to actuate the brake at a predetermined point along said path.

2. A spool carrier comprising a base, a frame, a spool carried by the frame, arcuate 70 slotted guides carried by the frame, a brake for the spool, and an automatic tension regulating device carried by the guides and adapted to actuate the brake at a predetermined point on the guides. 75

3. A carrier for braiding machines comprising a base, a frame carried thereon, a spool rotatably mounted intermediate the ends of the frame, a bearing sleeve carried by the frame above the spool, slotted guide 80 rails carried by the frame and partially encircling the spool, and a tension regulator adapted to travel along the guide rails and to movably engage the wire fed from the spool at a multiplicity of points along the 85 guide rails.

4. A carrier for braiding machines, comprising a base, a substantially vertical frame carried thereon, substantially parallel slotted curved guide rails carried by the frame, 90 a sleeve bearing mounted on the frame, a spool rotatably supported within the frame and having a winding adapted to pass upwardly through the sleeve, a tension regulator for the winding adapted to engage and 95 travel along the slots in the guide rails, said regulator having a roller over which the winding travels to support the regulator in a plurality of positions along the rails, and a brake for controlling the rotation of said 100 spool carried by the frame, said brake having an operating lever adapted to be actuated by said regulator when the latter is lifted to a predetermined position along the guide rails. 105

5. In a carrier for braiding machines, a base, a substantially vertical frame carried thereon, a spool rotatably supported within the frame, and intermediate the ends thereof, a brake device mounted on said frame for 110 controlling the rotation of the spool, a tension regulator movable in an arcuate path about said spool, a winding carried by said spool and adapted to normally support the regulator in a plurality of positions about 115 said spool, said regulator being adapted to release said brake from said spool when too great a tension is placed upon the winding fed from the spool.

6. In a carrier for braiding machines, a base, a substantially vertical frame carried thereon, a spool rotatably supported within the frame, and intermediate the ends thereof, a brake device mounted on said frame for controlling the rotation of the spool, a tension regulator movable in an arcuate path about said spool, a winding carried by 125 said spool and adapted to normally support the regulator in a plurality of positions about said spool, said regulator being adapt- 130

ed to release said brake from said spool when too great a tension is placed upon the winding fed from the spool, and means for varying the tension under which the regulator 5 will operate to set and release the brake device.

7. In a carrier for braiding machines, a base, a substantially vertical frame carried thereon, a spool rotatably supported within 10 the frame, and intermediate the ends thereof, a brake device mounted on said frame for controlling the rotation of the spool, a tension regulator movable in an arcuate path about said spool, a winding carried by said 15 spool and adapted to normally support the regulator in a plurality of positions about said spool, said regulator being adapted to release said brake from said spool when too great a tension is placed upon the winding 20 fed from the spool, and means for varying the tension under which the regulator will operate to set and release the brake device, said means including a plurality of detachable weighted plates adapted to be carried 25 by the regulator in its movement about the spool.

8. A carrier for braiding machines comprising a base, a frame, a spool carried by the frame, a brake for the spool, and an automatic tension regulating device movable in 30 a curved path about said spool and adapted to actuate the brake at a predetermined point along said path, said regulating device being adapted to engage a trip when in one 35 extreme position along its path of movement.

9. A carrier for braiding machines comprising a base, a frame, a spool carried by the frame, a brake for the spool, and an automatic tension regulating device movable 40 in a curved path about said spool and adapted to actuate the brake at a predetermined

point along said path, and rollers carried by said regulating device for engaging a trip when said device is in one extreme position 45 along its path of movement.

10. A carrier for braiding machines comprising a base, a frame, a spool carried by the frame, a brake for the spool, and an automatic tension regulating device movable in 50 a curved path about said spool and adapted to actuate the brake at a predetermined point along said path, and freely revoluble cones extending from said regulating device for engaging a trip where said device is in one 55 extreme position along its path of movement.

11. In a spool carrier for braiding machines, a base, a frame, a spool revolvably carried by said frame, substantially parallel 60 arcuate guide members carried by the frame and describing a path partially around said spool, a brake for the spool, and an automatic tension regulating device movable along said guides, said regulating device 65 comprising a strand receiving roller, and means carried by the device for exerting a constant predetermined pull on said device.

12. In a spool carrier for braiding machines, a base, a frame, a spool revolvably 70 carried by said frame, substantially parallel arcuate guide members carried by the frame and describing a path partially around said spool, a brake for the spool, and an automatic tension regulating device movable 75 along said guides, said regulating device comprising a strand receiving roller, and interchangeable means carried by the device for exerting a constant predetermined pull on said device.

In testimony whereof I hereunto affix my signature this 7th day of May, 1925.

COBURN F. VALLEY.
